TAILOR TACKER

Sidney Orthwin, Dayton, Ohio

Application June 25, 1953, Serial No. 364,164

4 Claims. (Cl. 101—368)

2

coated tailor's carbon, sometimes referred to as dress-maker's carbon, or one or two pieces of single coated tailor's carbon with the coated faces out, this carbon being placed preferably on the wrong side or the rear side of the material, so as to transfer the carbon to the rear side of the fabric by the use of a plunger or punch that is adjusted into position directly above the mark on the pattern, a slight tap or force being applied to the plunger so as to cause the carbon to be transferred to the fabric. The operative end of the punch or plunger may consist of a circular contour or it may consist of dashes or any other suitable contour.

Other objects and advantages reside in the construction of parts, the combination thereof and the mode of operation, as will become more apparent from the following description.

The reference markings of the pattern may consist of perforations or may consist of printed material on the tissue paper that is used in manufacturing the pattern. These reference marks may have to do with the location of buttons, button holes, darts, pleats, gathers, openings, etc.

Referring to the drawings:

Figure 1 is a perspective view of a pattern associated with the marking device disclosed herein.

Figure 2 is a side elevational view of the marker showing the pattern, the fabric and the parts associated therewith, in section.

Figure 3 is a top plan view of the marker shown in Figure 2.

Figure 4 discloses the marker used in association with a single layer of fabric.

Figure 5 is a fragmentary rear view of a piece of fabric that has been marked.

Figure 6 discloses an enlarged end view of the portion of the plunger coming in contact with the pattern of the preferred embodiment.

Figure 7 discloses a modification of the operative end of the punch.

Figure 8 discloses another modification of the punch.

The mechanism used in marking the pattern consists of two parts, that is, a plunger or punch and its support and the tailor's carbon or transfer material. The punch and the support therefor will now be described.

The punch 10 consists of a cylindrical member having a reduced portion that is threaded, as at 12, and a further reduced portion 14 that may terminate in a downwardly projecting cylindrical ring or tubular portion 16, the outer diameter of which is substantially the same as the diameter of the reduced portion 14. The center 18 of the reduced portion 14 may be countersunk or hollow, so that the marking portion of the punch may be referred to as being tubular. The punch is provided with a suitable head 20, which may be washer-like and fixedly secured to the end of the main body 10 or it may be upset, so as to be integral with the body 10.

The main body portion of the marker consists of a U-shaped leaf spring 30. The threaded portion 12 extends through an aperture in the U-shaped leaf spring 30, having a suitable aperture for the reception of the threaded portion 12. The aperture in the leaf spring member 30 may be threaded or the punch may be held in position by a nut 32 or other suitable means. If the aperture in member 30 is threaded, the nut 32 could function as a lock nut. If it is not threaded, the nut 32 locks the plunger in position. The leaf spring member 30 may be made from steel, brass or any other suitable material, whether metallic, plastic or wood.

The longer leg 30a of the U-shaped leaf spring member is adapted to lie on a table or a suitable flat support. The upper surface of the member 30a presents a smooth, flat uninterrupted area, which receives the impinging im-

This invention relates to marking sheet material, such as making marks upon fabric material cut according to a pattern, where the pattern is provided with markings to be used as directions when using the material cut from the patterns, although not necessarily so limited.

In the past, various methods have been used for transferring a mark from the pattern to the fabric. One method is the use of chalk to mark the fabric above a pin. Another is to use a thread basted or sewed in areas corresponding to the areas of the markings on the pattern. Devices have also been provided for marking the material by mechanically controlled chalk.

All previous devices using chalk are time-consuming because most of the patterns for garments, today, have reference marks printed on the pattern. This necessitates perforating the pattern at each and every reference mark to accomplish the desired result of marking two pieces of fabric or two places on a single-folded piece of fabric, simultaneously. Furthermore, the nature of the devices do not permit the fabric to remain in the flat fixed position in which it was cut. This results in the two pieces of fabric not holding their relative position while being marked. Therefore, the marks are not in register. The other methods to which I refer use no special devices and are cumbersome and time-consuming.

An object of this invention is to provide a device that enables the user to transfer all reference marks from a pattern, whether printed or otherwise, to two pieces of fabric or two different places on a folded piece of fabric simultaneously without having to perforate or remove the pattern from the fabric. This includes even the marking of the notch marks that are used for aligning one piece of fabric with another before stitching them together. Such notch marks are in the seam allowance and are usually cut into the fabric but in the case of sheer or delicate fabrics, this weakens the strength of the seam.

Another object of this invention is to provide a device, that because of its inherent design will always automatically give perfect registration between the two places being marked, because with only one punch to make both marks simultaneously, it is not dependent on the mechanical accuracy of two cooperating arms.

An object of this invention is to provide a marker that exerts pressure on the sheet material or the fabric in the areas marked on the pattern, so as to cause a transfer of material, such as carbon material, for making an impression or mark on the rear side of the fabric, without in any manner mutilating the fabric and without the use of pins, needles, thread, chalk and the like.

Another object of this invention is to transfer certain reference marks that appear on a pattern for making various kinds of clothing, whether the fabric consists of a single sheet or multiple sheets or is folded so as to consist of two halves, the marking of the fabric, preferably, but not necessarily taking place on the back side or wrong side of the fabric.

Another object of this invention is to use a double

pact of the member 14, and allows the layers of fabric material, carbon and pattern to lie smoothly together in true parallelism, uninterrupted by marking or other elements which are sometimes placed directly beneath the impinging members. The function of the marking element is performed by the double faced tailor's carbon. The under side of the leg 30a may be lined with felt, rubber or any other suitable cushioning material 34, so that the metallic U-shaped member when placed on a table will not tend to mar, scratch or mutilate a highly finished supporting surface. This has been represented by the layer 34. Instead of the punch terminating in a ring or tubular portion 16, it may terminate in any other suitable configuration, such as a star 40, shown in Figure 7, or in the form of a bar 42, shown in Figure 8.

The punch is used in association with a suitable transfer material 50 which is sometimes referred to as a tailor's carbon or dressmaker's carbon. This carbon 50 preferably has both sides coated with a suitable transfer material. Various types of transfer material are used, that is, various colors. For example, if a light colored fabric is used, conventional carbon material may be used, consisting of lamp black and a wax coating. However, this type of carbon will not prove satisfactory in the event the fabric is dark colored, as for example, black, blue and some of the other darker shades. For this type of fabric, a transfer material having pigments that are light in color, as for example, orange, white, red or some other suitable color, may be used.

The use of this transfer material and the punch will first be described where the goods or fabric is folded, so as to mark two identical halves simultaneously. The fabric has interleaved therebetween the double coated carbon 50, so that one layer 52 of fabric lies above the carbon and one layer below the carbon, as clearly indicated in Figure 2. The pattern 54 lies on top of the upper layer of fabric 52. This pattern 54 may have various markings, as for example, the crosses 56, the incisions 58, the darts 60, etc. The two layers of fabric, the transfer material or carbon sheet 50 and the pattern 54 are placed between the punch 14 and the lower leg 30a, as clearly shown in Figures 1 and 2. The punch 14 is aligned with a suitable mark on the pattern. When it has been so aligned, it is merely necessary to tap or hit or press on the head 20, so as to cause the punch 14 to impinge upon the fabric 52 and the carbon 50, so as to transfer the carbon 50 to the fabric, imprinting the marks 62, as shown in Figure 5, on the underside, or the side that the dressmaker may refer to as the wrong side of the material. In the case of darts, a series of impressions may be applied to the material, so as to outline the contour of the dart.

In the event a single layer of fabric is cut according to the pattern, the carbon paper or transfer material having both sides coated may be used by merely inserting a sheet of paper 64 over the lower leg 30a, then superimposing the carbon 50, the fabric 52 and the pattern 54, as clearly shown in Figure 4, so that when the punch is applied, the carbon is not transferred to the lower leg. Instead, an impression is made upon the sheet of paper 64, which may, after serving this purpose, be discarded. In the event a carbon having only one side coated is used, it will be necessary, when marking two layers of fabric simultaneously, either to use two sheets of carbon or to fold the carbon so as to have two exposed carbon surfaces.

In the event only one layer of fabric is to be marked with the use of carbon material having only one side coated, then the paper sheet 64 may be eliminated, in that the uncoated side of the carbon may then be placed upon the leg 30a.

The device disclosed herein is inexpensive to manufacture. There are no movable parts excepting the yield-

ing of the spring. It is dependable and efficient, long-lived and easily operated. The only part that deteriorates is the sheet of carbon material, which is readily available at a very small expenditure when replacement is required.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

1. A marker for duplicating connotations found on a garment pattern by impinging marks from a sheet of transfer material, said sheet having transfer material on both sides, upon a fabric having two layers, one layer being located below the transfer material and the other layer being located above the transfer material, said marker including a substantially U-shaped yieldable member, a punch fixedly mounted in one end of one leg of the U-shaped member, said punch being directed in a direction toward the other leg of the U-shaped member and normally held in spaced relation therefrom so that when the transfer material and the overlying and underlying fabric are positioned within the U-shaped member and rest upon said other leg the movement of the punch towards said other leg causes the transfer material to transfer a mark upon both layers of the fabric corresponding to the contour of the end of the punch, said other leg which constitutes an impact receiving member comprising throughout its upper area a smooth uninterrupted surface upon which the layers of the fabric may lie flat and in true parallel relationship.
2. A marker according to claim 1, wherein the punch constitutes a cylindrical member having a reduced portion provided with a hollow cavity functioning as a punch proper, the reduced portion being fixedly attached to the end of said one leg of the U-shaped member.
3. A marker according to claim 1, wherein the end of the punch is so formed as to cause the transfer material to impinge an easily recognizable characteristic mark upon the fabric.
4. A marker for duplicating connotations found on garment patterns by impinging marks from a transfer material upon fabric, said marker including a base, said base which constitutes an impact receiving member comprising throughout its upper area a smooth uninterrupted surface upon which layers of material may lie flat and in true parallel relationship, a punch, and means for resiliently mounting the punch in spaced relation from the base with the punch being directed towards the base so that as the fabric and transfer material is positioned between the base and the punch, the punch upon being hit will cause the transfer material to impinge upon the fabric.
